US00D985126S

(12) **United States Design Patent** (10) **Patent No.:** **US D985,126 S**
Li (45) **Date of Patent:** **** May 2, 2023**

(54) **BLOOD PRESSURE MONITOR**

(71) Applicant: **Shenzhen Finicare Co., Ltd.**, Shenzhen (CN)

(72) Inventor: **Chao Li**, Shenzhen (CN)

(73) Assignee: **Shenzhen Finicare Co., Ltd.**, Shenzhen (CN)

(**) Term: **15 Years**

(21) Appl. No.: **29/871,014**

(22) Filed: **Feb. 10, 2023**

(51) LOC (14) Cl. **24-02**

(52) U.S. Cl.

USPC **D24/165**

(58) **Field of Classification Search**

(57) **CLAIM**

The ornamental design for a blood pressure monitor, as shown and described.

DESCRIPTION

FIG. 1 is a front, right and bottom perspective view of a blood pressure monitor, showing my new design;

FIG. 2 is a rear, left and top perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

The broken lines shown in the drawings illustrate portions of the blood pressure monitor that form no part of the claimed design.

1 Claim, 8 Drawing Sheets
